UNITED STATES PATENT OFFICE.

OLIVER SCHLEMMER, OF CINCINNATI, OHIO.

WATER-HEATER.

SPECIFICATION forming part of Letters Patent No. 595,348, dated December 14, 1897.

Application filed January 9, 1897. Serial No. 618,663. (No model.)

To all whom it may concern:

Be it known that I, OLIVER SCHLEMMER, a citizen of the United States, residing at Cincinnati, Ohio, have invented new and useful 5 Improvements in Water-Heaters, of which the following is a specification.

My invention relates to the class of water-heaters commonly known as "sectional" water-heaters, consisting, essentially, of a fire-box and a number of superimposed (usually circular) sections having return water-passages extending horizontally and passages for the gases of combustion extending vertically through the same, said fire-box and sections being connected in common to passages for the feed and discharge of the water. Heaters of this class have come largely into use, being cheap and reasonably efficient for house-service in supplying "manifolds" or 20 "radiators" for heating apartments in cold weather; but their extended use has developed certain defects which it is the object of my invention to remedy. First, the sections being made of cast-iron and bolted at one or 25 both sides to the distributing-columns it is very necessary in order to avoid deposits of scale, mud, &c., in the sections and also to avoid cracks from unequal distribution of heat that the circulating currents should flow 30 freely through the horizontal sections. As these devices are usually constructed this condition is practically ignored, and the sections are often clogged and burned out or cracked by ordinary use. As contributing 35 to the second of these difficulties the sections are often constructed or put together in such manner as to create "pockets" where air is imprisoned and the distribution of heat impaired.

40 The first part or feature of my invention intended to cure the defects named consists in a construction of the heater-sections embodying a continuously-ascending water-passage from inlet to outlet, whose upper and lower walls have a like upward inclination tending, as hereinafter set forth, to facilitate the upward passage of the gases of combustion and to produce a circular or spiral movement of the ascending gases, whereby the 45 50 heat is better distributed through the series of superimposed sections.

The second feature of my invention relates to the distributing-column connecting the heater-sections. My improvement in this re-

gard is the construction of a vertical column 55 uniting all the sections and divided by a vertical partition into two channels, which I may designate as the "feed-in" and "feed-out" channels. The feed-in channel is continuous and open at both ends, connecting all 60 the feed-in ports of the sections with the fire-pot water-jacket below and the circulating-pipe above the heater. The feed-out channel is independent and connects the feed-out ports of the sections with the circulating-pipe 65 above.

These two improvements herein described may be employed separately; but the best results flow from their combination.

Mechanism embodying my invention is 70 illustrated in the accompanying drawings, in which—

Figure 1 is a plan view of one of the heater-sections; Fig. 2, a side or edge view, and Fig. 3 a perspective view, of same. Fig. 4 is a rear elevation of the entire heater complete with the distributing-column removed to exhibit clearly the different levels of the inlet and outlet ports. Fig. 5 is a face view of the distributing-column; Fig. 6, a side elevation of 80 the fire-pot, partly in section; and Fig. 7 is a perspective view of one of the heater-sections alternating in the complete structure with that shown in Figs. 1, 2, and 3, but shown in the present case with a modified construction 85 of the distributing-column.

Referring now to the drawings, A designates a heater consisting of a fire-pot *a*, upon which alternate heating-sections *b* are superimposed. The heating-sections consist of 90 shallow cylinders cored and cast to form a return water-passage around and between walled apertures *x* *y*, carried through the water-passages parallel to the axis of the cylinder. The general contour of these apertures 95 in the alternate sections *b* is indicated in Figs. 3 and 7, those of one section being elongated at an angle across those of an adjacent section in order to diffuse the gases of combustion and cause them to impinge more directly against the metal walls of the water-passages. Each section is provided with a central partition *z*, (shown in dotted lines in Fig. 1,) extending from one side partly across the hollow interior and with entrance and 100 egress ports *p* *p*², respectively entering one side of the section at opposite sides of the partition *z*. The two halves of the section 105

within the cylindrical ring r , constituting its exterior lateral wall, are inclined in opposite directions but at different levels, the inclination of one half starting at a lowest point and rising to a higher level at the opposite side, which level is the beginning of the backward inclination of the other half, as indicated in dotted lines in Fig. 2 and shown in perspective in Fig. 3.

10 The different levels of the ingress and egress ports are shown in Figs. 3 and 4, and in connection with the dividing-partition z there is thus formed in each section a continuously-ascending water-passage connecting the ingress-port p' with the egress-port p^2 , partially interrupted by the walled passages x or y , which subdivide the water-current, exposing it more completely to the heated walls of metal. The outer ring r extends sufficiently 20 above and below the interior walls to afford a proper seating of the sections one upon another, leaving space between for the proper circulation of the gases of combustion. The inclination of the upper and lower walls of 25 the sections, as will be readily understood, tends to deflect the upward current of the heated gases, giving them a whirling or spiral motion in each open space between sections, thus tending to distribute the heat more effectively, while the same inclination of the water-passages produces a free and rapid circulation of water without any possibility of imprisoning air in the sections.

30 The fire-pot construction is sufficiently indicated in Figs. 4 and 6, and consists of the usual water-jacketed cylinder a , into the annular space of which the water enters at the rear by a pipe connection a' at the bottom and leaves by a connection a^2 , directly over 35 said inlet. The novelty of construction lies in combining with the annular water-jacket of the fire-pot having inlet and outlet orifices, as described, a baffle-plate or partition a^3 , arranged horizontally between the inlet and 40 outlet orifices and dividing the annular space at the rear half of the water-jacket. The baffle-plate extends around the fire-pot proper 45 forward to a line about midway between the extreme front and rear. By its use the water is carried forward, as indicated by the 50 arrows, around the forward ends of the plate, at both sides equally, returning backward above to the outlet, thus equalizing the temperatures so far as to prevent unequal expansion, &c.

55 To complete the structure for use, it is necessary to add one or more distributing-columns. In the preferred form of apparatus I attach at the rear of the sections a single column E , which may be a single casing formed with ports at one side corresponding with the ports p' p^2 , as indicated in Fig. 5, and attached, as indicated in Fig. 1, or constructed in portions E' , cast with the sections, as shown 60 in Fig. 7, to form a complete column by the aggregation of the sections. The column thus formed is provided with a vertical partition

p , forming feed-in and feed-out channels p^3 p^4 , respectively, the former of which connects all the inlet-ports of the casings and opens 70 below to the water-jacket of the fire-box, through which the initial feed is derived, and the latter connects all the outlet-ports of the casings, but is closed just below the outlet-port of the lowest casing of the series. 75

Where, as in some constructions of this class, the feed-in channel is closed just above the inlet-port of the upper casing, it frequently happens that the upper casings obtain an insufficient supply of water by reason of the 80 exhaustion of supply caused by the drafts made upon the feed-in column by the lower casings of the series and steam is produced, which for various reasons is detrimental to the apparatus and otherwise objectionable. 85 In my improvement this difficulty is remedied by the open connection of both channels above to the circulating system, whereby in case of such exhaustion the excess needed for upper casings is supplied by downdraft from the 90 circulating-pipes, thus insuring at all times a full water-supply for all the casings. The general resulting effect is a better utilization of fuel and more rapid circulation through the entire apparatus. 95

I claim as my invention and desire to secure by Letters Patent of the United States—

1. A section for a water-heater of the character indicated, embodying a shallow cylinder divided nearly across by a diametrical 100 partition separating the exit-port from an adjacent inlet-port occupying different levels, thus producing a return-passage of continuous upward inclinations from front to rear and from rear to front, said passage being 105 pierced by vertical smoke-flues dividing the water-passage, substantially as set forth.

2. In a water-heater of the character indicated the combination of lateral heating-sections with inlet and outlet orifices independently adjacent at one side, and a partitioned distributing-casing connecting all the receiving-ports of the sections in one channel and all the discharge-ports of the sections in a second channel, both channels communicating 115 with the circulating-pipe of the distributing system, substantially as set forth.

3. In a water-heater of the character indicated, the combination of a series of superimposed water-heating sections each having 120 adjacent inlet and outlet ports at different levels and a return water-passage inclined upwardly from the inlet-port to the rear and from the rear to the outlet-port, and a vertical shell covering all of said ports and constituting a 125 single water-distributing column, substantially as set forth.

In testimony whereof I have hereunto set my hand in the presence of two subscribing witnesses.

OLIVER SCHLEMMER.
